UNITED STATES PATENT OFFICE.

JOHN A. LAMONT, OF GRANITE CITY, ILLINOIS, ASSIGNOR TO AMERICAN STEEL
FOUNDRIES, OF NEW YORK, N. Y., A CORPORATION OF NEW JERSEY.

SWING-TRUCK.

1,151,694.

Specification of Letters Patent. Patented Aug. 31, 1915.

Application filed June 1, 1915. Serial No. 31,455.

To all whom it may concern:

Be it known that I, JOHN A. LAMONT, a citizen of the United States, and resident of Granite City, in the county of Madison and 5 State of Illinois, have invented certain new and useful Improvements in Swing-Trucks, of which the following is a specification.

My invention relates to railway car trucks and has particular reference to a novel 10 swing or lateral motion truck.

Many railroads prefer to utilize a car truck in which the bolster shall be adapted for lateral movement with relation to the side frames of the truck. This result is secured by the utilization of many different 15 forms of mechanical devices and the present construction is intended as an improvement thereon.

One of the objects of the present invention 20 is to provide for maximum spring capacity and for the distribution of the load carried by the springs over a greater area and to bring the support for the springs nearer to the axles of the truck, whereby less strength 25 and rigidity is required of the side frames. This result is secured in the present instance by spacing apart the two pairs of springs, bringing each pair a material distance closer to the car axles and supporting a bolster on 30 a bail in the usual location. This results in a construction in which lateral motion of the bolster is permitted and in which the size and capacity of the springs is not limited by the usual space provided between the col- 35 umns of the truck.

The invention will be more readily understood by reference to the accompanying drawings, wherein—

Figure 1 is a side elevation of a car truck 40 constructed in accordance with my invention; Fig. 2 is a bottom plan view thereof, and Fig. 3 is a section on the line 3—3 of Fig. 1.

Referring more particularly to the drawings, it will be seen that the side frame contemplated by me is an integral structure 45 comprising compression member 10, tension member 11, columns or struts 12 and pedestal jaws 13, between which a journal box 14 is adapted to be received and held. Between the two struts 12 an opening is provided within which the end 15 of a bolster is adapted to project. The bolster on its lower surface near the ends is provided with an 55 ear 16, to which is secured a shoe 17. On

the lower surface of the shoe I provide marginal flanges 18. The upper surface of the shoe is curved to correspond to the curvature of the ear 16, and rotary movement is possible between the shoe and the ear. The 60 shoe 17 rests upon and the flanges 18 engage the lower portion 19 of a U-shaped support or bail 20. Apertures are provided in the upper ends of the bail, and a shaft 21 extends through the apertures and through an 65 elongated opening 22, shown in dotted lines in Fig. 3, in the columns 12 of the side frame. The ends of the shaft 21 engage spring caps 23, located outside of the struts, which caps rest upon springs 24, two series of spring 70 being preferably placed beneath each cap. These springs rest within pockets 25, formed integral with the side frame.

It will be seen that the springs 24 are located considerably nearer to the axles of the truck than has commonly been the practice. 75 Also that the size and capacity of the springs is not limited, due to the increased space within which such springs may be located. Such construction provides for the ready 80 dismantling of the truck without removing bolts or rivets, it merely being necessary to jack up the bolster sufficiently to disengage the bail from the lower portion thereof, whereupon the bolster may be removed longitudinally through the opening between the 85 columns. In some cases it may be necessary to remove the shaft 21 to provide sufficient space for the removal of the bolster.

I claim:

1. In a car truck, the combination of a side frame having columns, a bail mounted between said columns, a pivot for said bail, and springs located outside of said columns and providing a support for said pivot, substantially as described.

2. In a car truck, the combination of a side frame having a bolster opening, a bail in said opening, a bolster mounted on said bail, a pivot for said bail, said pivot projecting through said columns, and springs mounted outside of said columns and providing a bearing for said pivot, substantially as described.

3. In a car truck, the combination of a side frame having columns providing a bolster opening, a bail mounted in said opening, a shaft supporting said bail, the ends of which shaft project through said columns, spring seats provided on said frame outside 105 110

of said columns, springs mounted on said seats, and spring caps providing bearings for the ends of said shaft, substantially as described.

- 5 4. In a car truck, the combination of a side frame having columns providing a bolster opening therebetween, a bolster in said opening, a bail for supporting said bolster, a shaft acting as a pivot for said 10 bail, springs mounted outside of said col-

umns, and spring caps resting on said springs and providing bearings for said shaft, substantially as described.

Signed at Granite City, Illinois, this 24 day of May, 1915.

JOHN A. LAMONT.
